UNITED STATES PATENT OFFICE.

JAMES C. BEARD, OF BINGHAMTON, NEW YORK, ASSIGNOR TO LEWIS M. WEED CO. INC.,
A CORPORATION OF NEW YORK.

LEGGING.

1,270,364.

Specification of Letters Patent. Patented June 25, 1918.

Application filed January 21, 1918. Serial No. 213,004.

To all whom it may concern:

Be it known that I, JAMES C. BEARD, a citizen of the United States, residing at Binghamton, in the county of Broome and 5 State of New York, have invented certain new and useful Improvements in Leggings, of which the following is a specification.

This invention relates to garments, and more particularly to means for reinforcing 10 the edges of such garments as leggings and gaiters and for preventing the wrinkling, buckling or bulging thereof.

An object of this invention is to provide such garments with reinforcing and stiffening 15 means which will not inconvenience or distress the wearer, and which will comfortably and readily respond to movements of the wearer and conform to wide variations either in the figure of the wearer or in the 20 thickness, form and manner of folding or arranging the clothing over which such garments may be worn.

Other objects are to provide such garments with reinforcing or stiffening means 25 which is adapted for use with equal facility with either lace or buckle fasteners, which is inexpensive to produce and apply, and which is durable and lighter than those heretofore known and used.

30 Other objects and advantages of this invention will be in part obvious and in part specifically set forth in the annexed specification.

This invention is illustrated by the annexed drawing in which—

Figure 1 is an elevation of a lace fastened legging embodying this invention,

Fig. 2 is an elevation of a pair of the reinforcing or stiffening members,

40 Fig. 3 is an enlarged view of the upper end of the structure shown in Fig. 2,

Fig. 4 is an enlarged sectional view taken along the line 4—4 of Fig. 1, and

Fig. 5 is an elevation of a buckle fastened 45 legging embodying this invention.

Referring now in greater detail to Fig. 1,—the legging or gaiter body therein shown comprises the flap 21 which overlaps the flap 22, and the foot strap 23 suitably secured to the adjacent sides of the lower end of said body.

Near the edges of said flaps 21 and 22, and extending substantially the entire length thereof, are provided the resilient reinforcing and stiffening members 24 and 25. Said

members being held in position and suitably covered by material of the flaps, said flaps being seamed so as to provide vertical passages inclosing said members, (see also Fig. 4).

It is important that these members 24 and 25 should possess flexibility perpendicularly to the surface of the flaps to which they are attached, such as the flexibility which is afforded by the flat stiffening members heretofore similarly employed, and furthermore, to obtain a wide range of adaptability of the legging to various wearers, and to enable the legging to comfortably conform not only to the shape of the leg of the 70 wearer and to underlying clothing, but to also readily respond to the movements of underlying muscles, it is very desirable that the stiffening members thus employed should be flexible in a plane parallel to the surface 75 of the flaps, while possessing suitable elasticity for resisting undue distortion and for restoring the garment to its normal shape when distorting influences are not present.

To these ends the members 24 and 25 are 80 shown to be of circular cross section, but may be of other suitable cross section as, for example, square or hexagonal. The material of these members should be of such variety and temper as to afford a suitable 85 degree of flexibility and resiliency, as, for example, spring steel wire. In any event, the size, shape and material of said members should be such that they will be adapted to act to effectively prevent wrinkling, and will 90 suitably resist distortion of said flaps, while yielding to flexures both perpendicularly to and laterally of said flaps with sufficient facility to enable the legging to comfortably adjust itself to wide variations in the 95 shapes of the legs of different wearers and in the thickness and arrangement of the clothing over which such legging is worn, and to readily respond to the movements of the muscles in the leg of the wearer.

By so forming these stiffeners as to avoid sharp corners and edges at the ends thereof, the wear upon the material of the flaps incident to use will be greatly decreased. For this reason, ends of these members are 105 curved as shown, and for convenience and economy in manufacture, said members may be made in pairs by so bending a piece of suitable spring wire as to form an elongated U-shaped piece, the sides of which 110

form said stiffening members, the upper ends of said members being so united as to present a similarly curved outline.

If preferred, both ends of the respective members may be united and inclosed by means of a sheet metal sheath, such as the sheath 27 most clearly shown in Fig. 3, and in any event the upper ends of the members 24 and 25 should be united, as by such a 10 sheath.

In employing a sheath such as shown, the end 28 of the member 24 is curved toward the adjacent end of the member 25, to conform to a channel provided therefor 15 in said sheath 27. Said sheath being so pressed around said curved end as to be firmly secured thereto, and thereby affords such relative stability of said members as to tend to maintain them in a fixed plane 20 by preventing the rotation of said sheath with relation to the member 24. The straight end 29 of the member 25 is loosely confined by the sheath 27, so that said end 29 may slide longitudinally in the channel 25 provided therefor in said sheath. Were it not for the sliding movement thus permitted, the symmetrical flexure of the members 24 and 25 in a plane parallel to the surface of the flap would be seriously impaired. 30

The fastening means provided for holding the flaps 21 and 22 together comprises the lace 30, the lower end of which is suitably secured to the inside of the flap 22, 35 from which fastening said lace passes through the gromet 31, thence across said flaps to and through the gromet 32, thence upwardly between said flaps to and through the gromet 33, thence outside of said flaps 40 and around the hook 34 to and through the gromet 35, thence upwardly between said flaps to and through the gromet 36, thence outside of said flap 21 around the hook 37 to and through the gromet 38, thence between said flaps 21 and 22, across the top of the flap 21 to the point 39 where the upper end of said lace is suitably tied. 45

In Fig. 1 the members 24 and 25 are shown in a position which they would assume were 50 the portion of the legging above the hook 34 expanded to a relatively greater extent than the portion of the legging below said hook, the portions of said members secured to the flaps 21 and 22 being curved away 55 from one another above said hook 34 and, rocking around the fulcrum provided by the fastenings 33, 34 and 35. The portions of said members below these fastenings are curved toward one another, thereby drawing 60 the lower portion of the legging snugly around the wearer.

The hooks 34 and 37 may be secured by means of gromets as indicated by Fig. 4, or may be held in position by means of 65 clenched tangs or otherwise as desired, and

these hooks and the gromets 31, 32, 33, 35, 36 and 38 are applied to the material of the flaps 21 and 22 between the stiffeners 24 and 25 secured respectively thereto. In any event it is evident that these fastenings may 70 be applied with much greater convenience and more speed than if it was necessary to exactly locate them with relation to openings which might be provided therefor through the stiffening members themselves, 75 such as have been heretofore employed in using flat strip stiffening members, and that the desired degree of stability is given these fasteners.

Referring now to Fig. 5,—the flaps 21 80 and 22, the foot strap 23 and the stiffening members 24 and 25 are similar to the corresponding parts shown in Fig. 1, these flaps being fastened together by means of the adjustable buckles 41, 42 and 43, which 85 are suitably attached to the material of said flaps between the stiffening members 24 and 25 secured respectively thereto, as by the use of suitable gromets or clenched tangs. It will thus be obvious that, when 90 leggings have been made up in quantities without fasteners, in accordance with this invention, any one of various types of fastening means may thereafter be conveniently applied to the material of the flaps between 95 the stiffening members without the necessity of punching or locating corresponding holes through the stiffening members, as would be necessary to obtain a corresponding degree of stability and reinforcement 100 if flat strip stiffeners were employed in accordance with the methods heretofore used.

In Fig. 4 the stiffening members 24 and 25 are shown in the position which they assume when not subjected to distorting influences. 105

It is believed that the operation and use of this invention is rendered obvious to those skilled in this art by the foregoing description, and same will therefore not be 110 herein further described.

What I claim and desire to secure by Letters Patent of the United States is:

1. In a legging having overlapping side flaps,—spaced resilient stiffening members with suitably joined ends secured adjacent to the edge of the outer one of said flaps and extending substantially the entire length of said flap, said members being of such form and material as to readily yield 115 to flexure both perpendicularly to and along a plane parallel to said flap.

2. In a legging having overlapping side flaps,—spaced resilient stiffening members with suitably joined ends secured adjacent 120 to the edge of the outer one of said flaps and extending substantially the entire length of said flap, said members being of such form and material as to readily yield 125 to flexure both perpendicularly to and along 130

a plane parallel to said flap, and suitable uniting means for said flaps, said uniting means being secured to portions of said outer flap situated intermediate of the said

5 members.

3. In a legging having overlapping side flaps,—an elongated U-shaped piece of spring wire secured to one of said flaps adjacent to the edge thereof, one of the ends 10 of said wire being curved toward the other of said ends, and a sheet metal member enclosing the ends of said wire and so pressed around said curved end as to be retained in suitable relation to said ends.

4. In a legging having overlapping side flaps,—an elongated U-shaped piece of spring wire secured to one of said flaps adjacent to the edge thereof, one of the ends 15 of said wire being curved toward the other of said ends, and a sheet metal member so pressed around said curved end as to be firmly secured thereto and loosely confining the other end of said wire.

In witness whereof, I hereunto subscribe my name, this 16th day of January, A. D. 25 1918.

JAMES C. BEARD.
